CIGARETTE DISPENSER

Karl F. Keyzer, Rockford, Ill.

Application December 12, 1947, Serial No. 791,260

10 Claims. (Cl. 312—83)

1

This invention relates to a cigarette dispenser having a member manually movable to release the cigarettes one at a time employing a construction generally similar to that shown in Patent No. 1,798,680 upon which the present invention is an improvement.

One object is to provide, in a dispenser of the above character, a novel means for agitating the cigarettes during each dispensing operation whereby to prevent clogging of the dispenser and always insure the release of one cigarette.

A more detailed object is to provide a vertically movable slide forming the rear wall of the container and actuated automatically as an incident to each dispensing operation.

The invention also resides in the novel and simple means employed to actuate the slide and also return the closure member to closed position.

Other objects and advantages of the invention will become apparent from the following detailed description taken in connection with the accompanying drawings, in which

Figure 1 is a perspective view of the improved dispenser.

Fig. 2 is a perspective view of the moving parts.

Figs. 3 and 4 are vertical sectional views taken along the line 3—3 of Fig. 2 and showing the parts in different positions.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

In the form shown for purposes of illustration, the cigarettes 9 to be dispensed are stored in a rigid generally rectangular box formed by a flat front wall 10 slightly wider than the length of a cigarette, a rear wall 11 of similar size, and narrower connecting side walls 12. Screws 13 may be entered through holes in the rear wall to secure the box to any desired support. The upper end of the box is closed by a cover 14 swingable about pivot pins 15 projecting through the side walls near the upper end of the box. Herein, the bottom of the box is formed by a downwardly and forwardly inclined extension 16 on a slide 17 which lies against the rear box wall 11 and is movable vertically along guides 18 defined by grooves 19 formed in the side walls 12 on the inner side thereof. At its forward end, 55

2

the bottom 16 bends downwardly as indicated at 20 into parallelism with the front wall 10 but is spaced in front of the latter a distance slightly greater than the diameter of a cigarette so that a cigarette disposed horizontally in the opening 21 thus formed will fall sidewise and downwardly.

The bottom opening 21 is normally closed (Fig. 3) by a generally flat member 22 mounted beneath the box for horizontal movement rearwardly between a releasing position (Fig. 4) and a closed position (Fig. 3). To this end, arms 23 upstanding from opposite ends of the member 22 lie alongside the outer surfaces of the side walls 12 and are suspended at their upper ends from the pivots 15. Lugs 24 project forwardly from the member 22 and are curved to provide a recess 25 for receiving the lowermost cigarette when the member is, by engaging one 26 of the lugs or other part rigid with the member, pushed rearwardly to bring the recess 25 into alignment with the discharge opening as shown in Fig. 4. Then, as the member 22 is again moved forwardly to close the bottom opening, the cigarette received in the recess 25 is carried forwardly beneath the front wall to a dispensing position (Fig. 3) in front of the box. The cigarette is thus supported in a position readily accessible for withdrawal manually.

In accordance with the present invention, provision is made for raising and lowering the slide 17 and thereby agitating the cigarettes in the box automatically as an incident to each dispensing operation. This may be accomplished simply through engaging cam surfaces 26 and 27 on the member and slide respectively. Herein, the surface 26 is the upper edge of a flange 28 turned upwardly along the rear edge of the member 22. The surface 27 is the downwardly and rearwardly inclined edge of a block 29 disposed below and rigid with the underside of the bottom 16. By inclining the edge 27 at approximately forty-five degrees, the weight of the slide 17 may be utilized advantageously to urge the member 22 forwardly when the manual pressure thereon is released. The necessity of providing a spring for returning the member is thus avoided.

In operation, the parts are normally disposed in the positions shown in Figs. 1 to 3, one cigarette being disposed in the opening 21 and resting on the closure member 22 as shown in Fig. 3. The other cigarettes are arranged irregularly above the cigarette next to be dispensed, some resting on the inclined bottom 16 and others

against the slide 17. Now, as the member 22 is pushed rearwardly, all of the cigarettes except the lowermost one are moved within the box and thus agitated so that one or more cigarettes come to rest in horizontal position in the opening 21 which, it will be observed from Fig. 4, is extended vertically and thus adapted to receive two or more cigarettes disposed horizontally the one above the other and thus positioned for proper passage through the opening 24 in succeeding dispensing operations. Such position, at least of the lowermost cigarette, is retained as the member 22 is released and again allowed to move forwardly under the weight of the slide 17. By such agitation of the cigarettes which occurs as an incident to each dispensing operation, the danger of the cigarettes clogging or becoming wedged in the entrance to the discharge opening is avoided effectively.

The vertical movement of the slide 17 and the bottom 16 is preferably greater than the diameter of a cigarette. To prevent a cigarette from rolling rearwardly in beneath the lower edge of the extension 29 at this time, two lugs 30 depending from this edge are positioned to hold the cigarettes from rolling backwardly as shown in Fig. 4. Then, when the slide is lowered, these lugs move downwardly into holes 31 in the member 22.

The cigarette dispenser described above is simple in construction and operation and operates reliably at all times so as to insure the dispensing of only one cigarette at a time but always one cigarette in each operation.

I claim as my invention:

1. A cigarette container having, in combination, front and side walls, a rear wall cooperating with said front and side walls to form a box and having a forwardly and downwardly inclined extension forming a bottom for said box and cooperating with said front wall to form a discharge opening approximating the width and length of a cigarette disposed horizontally, means rigid with and disposed below said extension providing a downwardly and rearwardly inclined cam surface, a member disposed below said front wall and normally closing said discharge opening and having a forwardly projecting receptacle to receive a single cigarette through said opening when aligned with the latter and support the cigarette in front of said front wall when the member is moved forwardly, arms at opposite ends of said member extending upwardly alongside said side walls, means near the upper end of said front wall and adjacent the latter suspending said arms for movement of said member backwardly and forwardly, and means on said member engageable with said cam surface and operable to move said rear wall upwardly as said member is moved rearwardly to bring said receptacle beneath said discharge opening.

2. A cigarette container having, in combination, front and side walls, a rear wall cooperating with said front and side walls to form a box and having an extension forming a bottom for said box and cooperating with said front wall to form a discharge opening for passing a horizontally disposed cigarette, a downwardly and rearwardly inclined cam surface rigid with the underside of said bottom, a member disposed below said front wall and normally closing said discharge opening but releasing a cigarette therefrom when moved rearwardly, arms at opposite ends of said member extending upwardly alongside said side walls, a pivot suspending said arms to permit sub-

stantially horizontal movement of said member backwardly and forwardly, and means on said member engageable with said cam surface and operable thereon to move said rear wall upwardly as said member is swung rearwardly.

3. A dispensing cigarette container having, in combination, a box having front, rear and side walls, a slide guided for vertical movement along the rear of said box and having a downwardly and forwardly inclined extension turned downwardly at its forward end and spaced from said front wall to form therewith an opening for passing cigarettes downwardly, a member normally closing said opening and mounted beneath the opening for horizontal movement rearwardly and forwardly, said member when shifted rearwardly releasing a cigarette through said opening, and surfaces on said slide and said member coacting when said member is pushed rearwardly to raise said slide, said surfaces acting under the weight of the slide when said member is released to shift the member forwardly.

4. A dispensing cigarette container having, in combination, a box having front, side and rear walls, a slide disposed in front of said rear wall and guided for vertical movement, said slide having a downwardly and forwardly inclined extension turned downwardly at its forward end into parallelism with said front wall to form therewith an opening for passing cigarettes sidewise and downwardly, a member normally closing said opening and mounted beneath the opening for horizontal movement rearwardly and forwardly, said member when shifted rearwardly releasing a cigarette through said opening, and cam surfaces on said slide and said member coacting during said rearward movement to raise said slide and agitate the cigarettes then disposed in said opening.

5. A dispensing cigarette container having, in combination, a box having front, side and rear walls, a slide disposed in front of said rear wall and guided for vertical movement, said slide having an extension forming the box bottom and cooperating with said front wall to provide an opening for passing cigarettes downwardly, a member normally closing said opening and mounted beneath the opening for horizontal movement rearwardly and forwardly, said member when shifted rearwardly releasing a cigarette through said opening, and surfaces on said slide and said member coacting to raise said slide during said rearward movement and to lower the slide during said forward movement.

6. The combination with a container having a bottom opening adapted to pass a single cigarette sidewise therethrough, said opening being defined in part by a slide guided for vertical movement, a member mounted beneath said container for movement back and forth and having a recess adapted to receive a cigarette when disposed beneath said opening and operable to carry the cigarette to a dispensing position in front of said container as the member is moved forwardly, said member closing said opening when in said dispensing position, and cam surfaces on said member and said slide coacting as said member is shifted rearwardly and forwardly to respectively raise and lower said slide and agitate the cigarettes disposed in and adjacent said opening.

7. The combination with a container having a bottom opening adapted to pass cigarettes sidewise therethrough, said opening being defined in part by a vertical wall on a slide guided for verti-

cal bodily movement and operable in such movement to agitate the cigarettes disposed in said container above said opening, a member mounted beneath said container for horizontal movement back and forth to release a cigarette therethrough when shifted rearwardly, said member closing said opening when in its forward position, and means on said slide acting during rearward shifting of said member to raise said slide.

8. The combination with a container having a bottom opening adapted to pass cigarettes side-wise and downwardly therethrough, a member mounted on said container beneath said opening for movement back and forth to open and close the opening, a slide within said container contacting the cigarettes therein and having a vertical surface defining the rear wall of said opening, and means actuated by the movements of said member to raise and lower said slide bodily and thereby agitate the cigarettes in said container.

9. The combination with a container having a bottom opening adapted to pass cigarettes side-wise and downwardly therethrough, said opening being defined in part by a vertical wall on a slide guided for vertical bodily movement and having a bottom inclined upwardly and rearwardly from the top of said vertical wall, a member mounted beneath said container for horizontal movement back and forth to release a cigarette therethrough when the member is shifted rearwardly, said member closing said

opening when in its forward position, and means providing an operative connection between said member and said slide acting during rearward shifting of said member to raise said slide bodily.

- 5 10. The combination with a container having a bottom opening adapted to pass cigarettes side-wise therethrough, said opening being defined in part by a slide guided for up and down motion within the container and having a bottom wall inclined upwardly and rearwardly from said opening at an angle which remains constant relative to the horizontal in all vertical positions of the slide, a member mounted beneath said opening for movement back and forth to open and close the opening, and means actuated by the movement of said member to raise and lower said slide bodily and thereby agitate the cigarettes disposed in said container above said bottom wall.
